CLAIM

An ornamental design for a vaporizing device outer lid and basket assembly, as shown and described.

DESCRIPTION

FIG. 1 is a perspective view of the vaporizing device outer lid and basket assembly;

FIG. 2 is a top view of the vaporizing device outer lid and basket assembly;

FIG. 3 is a bottom view of the vaporizing device outer lid and basket assembly;

FIG. 4 is a side view of the vaporizing device outer lid and basket assembly; and,

FIG. 5 is a frontal view of the vaporizing device outer lid and basket assembly.

The broken line showing of a heating chamber is included for the purpose of illustrating environmental structure and forms no part of the claimed design.

1 Claim, 1 Drawing Sheet
